UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER FOLDING BOX.

Application filed March 23, 1922. Serial No. 546,020.

To all whom it may concern:

Be it known that I, SAMUEL BERGSTEIN, a citizen of the United States, residing at Middletown, in the county of Butler and State of Ohio, have invented certain new and useful Improvements in Paper Folding Boxes and the like, of which the following is a specification, reference being had thereto in the accompanying drawings.

10 This invention relates to improvements in paper boxes, having particular reference to paper folding boxes.

The main object of my invention is to provide a folding paper box, of the knock-down type, which will be cheaper to produce, and which will be stronger and more durable than ordinary types of paper folding boxes of this character.

Under the present practice of making 20 paper folding boxes, various methods are employed in forming and assembling the boxes,—the most common practices being to use staples for fastening different parts of the separate units of the box together; or 25 fastening the parts one to another by means of suitable slots and inserts,—one part having a slot and the coacting part an insert adapted to enter the slot whereby to interengage the parts; or to unite the contacting 30 surfaces of overlapping parts by any suitable adhesive substance.

In all methods of the known practice, more or less hand work is required to assemble the boxes which adds relatively high 35 percentages to the cost of production; also in certain common types of folding boxes the percentage of waste material is relatively high, and all these common types of paper folding boxes lack the strength and 40 stability necessary to make the boxes in all respects suitable for average requirements.

The improved paper folding box of the present invention is adapted for complete production on an automatic paper box making machine,—handwork being entirely 45 eliminated, and production accordingly cheapened. One unit of the improved box, in its preferred form, has twice-folded ends, and the other unit twice-folded sides, the 50 folded portions being joined together by any suitable adhesive, as glue, paste, cement, etc.,—the corners of both units also being formed of double thickness of material glued together, thus the sides and ends of the boxes 55 as assembled have triple strength and the

corners quadruple strength, and are far better adapted to withstand the usage to which they are put.

A further object of my invention is to provide an improved folding box of the character described which will be in knock-down form as delivered from the automatic machine,—thus to obtain close uniformity of construction and to further cheapen the product by eliminating hand operation, and minimizing machining operations; also the top and bottom units of the box, as delivered from the folding machine are adapted for immediate assembling—one unit with the other—without setting-up of the separate units, as required in boxes made by the common practice.

In the accompanying drawings, my improved folding box is shown in a preferred form of construction,—it being understood 75 that the drawings serve merely to illustrate the invention, and that various modifications can be made relative to details of the arrangement without departing from the underlying principles of design and construction.

In the drawings:

Fig. 1 is a full plan view of the blank for forming the bottom of the box;

Fig. 2 is a full plan view of the blank for forming the top of the box;

Fig. 3 is a detail of the blank for the top of the box illustrating the first and second steps of folding;

Fig. 4 is a detail of the blank for the bottom of the box illustrating the first and second steps of folding;

Fig. 5 is a detail of the blank for the bottom of the box illustrating the final 95 steps of folding;

Fig. 6 is a detail of the blank for the top of the box illustrating the final folding;

Fig. 7 is a plan view of the completed bottom of the box opened;

Fig. 8 is a plan view of the completed 100 top of the box opened, and

Fig. 9 illustrates the complete assembly of the box.

The blanks —A and —B, as shown in Figs. 1 and 2, for forming the top and bottom respectively of my improved box, may be produced by any well known method of paper cutting or blanking.

As here shown, the blanks —A and —B consist of integral parts, slotted on the lines 110

—1 and scored on the lines —2—3—4—5—6—7 to form the corners and to effect straight-line folding of the different portions of the blanks. While scoring of the blanks is not essential to the successful practice of the invention, it is desirable, where certain grades of paper stock are used, to prevent breaking of the paper on the folding lines, and also to effect more symmetrical, straight-line folding of the different parts.

As illustrated in Fig. 4, the first step of forming the bottom of the box from blank —A consists in folding the portions —C inwardly on score lines —4,—the next step 15 consisting in applying glue, or other effective adhesive, to the entire surfaces —D and —d of the blank,—the second step of forming consisting in folding the portions —E on lines —7 over the portions —D, as illustrated in Fig. 4, and applying pressure to 20 the fold to effect a firm adhesion between the opposite contacting surfaces; the third and final step of forming the bottom of the box, consisting in folding on lines —6 the entire portions —D and —d, including the 25 portions —E secured thereto, inwardly, thus bringing the adhesive surfaces —d—d in contact with the folded portions —c—c, and completing the operation under pressure to 30 form a firm adhesion of the parts one to another,—the bottom of the box as completed having double thickness of material at both ends, and around the corners, and being in knock-down form as illustrated in 35 Fig. 5,—the sides —F, as here shown, having but a single thickness of material. The diagonal edges of portions C—E and C—d match one with the other as the parts are 40 brought together, as indicated in dotted lines —8 in Fig. 5,—thus effecting symmetrical junctures and continuity of the double thickness of material over the ends and around the corners of the box,—the end 45 corners being formed on lines —2 and —3, and the bottom corners on lines —5—6 as the unit is opened.

The top of the box is formed from blank —B substantially in the same manner as the bottom from blank —A, except that the 50 double thickness of material is arranged at the sides and around the corners, instead of at the ends and around the corners. Thus the first step in forming the top consists in folding parts —g inwardly on lines —4, as indicated in Fig. —3,—the second step consisting in applying the adhesive to the entire surfaces of the portions —H—h,—the second forming operation consisting in folding portions —I on lines —7 upon portions 55 —H and causing adhesion of the parts one with the other under pressure as described in connection with the formation of the bottom of the box,—the third and final step of the operation consisting in folding the 60 portions H—h and —I on lines —5, as in- 65

dicated in Fig. 6,—thus causing the adhesive surfaces of parts —h to contact under pressure with the surfaces —g to join the parts together,—the diagonal edges of portions g—I and g—h matching one with the other, as indicated by dotted lines —9 in Fig. 6, as in the case of blank —A, to effect symmetrical junctures and to cause the double thickness of material to extend the full length of the sides and around the corners of the box, in a manner similar to the construction of the ends and corners of the bottom of the box,—the ends —J of the top of the box, as here shown, being formed of a single thickness of material, and the 70 top of the box as completed being in knock-down form as indicated in Fig. 6,—the end corners of the unit, as opened, being formed on lines —2—3 and the top corners on lines —5—6.

The complete assemblies of the box are illustrated in Figs. 7, 8 and 9,—Fig. 7 illustrating the bottom, and Fig. 8 the top of the box opened, ready to be assembled one with the other, as illustrated in Fig. 9. It 75 will be observed that in the complete box, as illustrated in Fig. 9, the sides and ends of the box have triple thickness of material, and the four corners quadruple thickness of material,—thus forming a box of symmetrical construction throughout, having rugged strength and durability, and being adapted for cheap production with a minimum waste of material.

Having described my invention, I claim: 100

1. In a folding box, including in combination with a blank for forming a unit of said box, the corners of the blank being slotted, and portions thereof folded inwardly, opposite outwardly extended portions of said blank folded inwardly, and secured to adjacent margins thereof, and a second time folded with said margins,—the unoccupied portions of said margins being secured to the folded portions of said corners whereby to 105 effect multiple thickness of the material of the blank over the corners and on opposite sides of said box.

2. In a folding box, including in combination with a blank for forming a unit of said box, the corners of the blank being slotted diagonally and portions thereof folded inwardly, opposite outwardly extended portions of said blank having diagonal edges, folded inwardly and secured to adjacent margins thereof, and a second time folded with said margins to cause said diagonal edges to match corresponding edges of the inturned portions of said corners,—the unoccupied portions of said margins being secured to the folded portions of said corners whereby to 110 effect multiple thickness of the material of the blank over the corners and on opposite sides of said box.

3. In a folding box, including in combina- 115

- tion with a blank for forming a unit of said box, the corners of the blank being slotted diagonally and portions thereof folded inwardly, opposite outwardly extended portions of said blank having edges cut diagonally, folded inwardly and secured to adjacent margins thereof, and a second time folded with said margins to cause said diagonal edges to match corresponding edges of the inturned portions of said corners, and the diagonally-cut edges of said margins to match the folding line thereof,—the unoccupied portions of said margins being secured to the folded portions of said corners whereby to effect multiple thickness of the material of the blank over the corners and on opposite sides of said box.
4. In a folding box, including in combination with a blank for forming a unit of said box, the corners of the blank being slotted and portions thereof folded inwardly, opposite outwardly extended portions of said blank folded inwardly and secured to adjacent margins thereof, and a second time folded with said margins,—the unoccupied portions of said margins matching the inturned portions of said corners and secured thereto,—the outer edges of the margins and the folding line of the portions secured thereto being substantially on a straight line and matching an edge of the folded portions of said corners.
5. In a folding box, including in combination with a blank for forming a unit of said box, folding lines scored on said blank, the corners of the blank being slotted and portions thereof folded inwardly, opposite outwardly extended portions of said blank folded inwardly and secured to adjacent margins thereof, and a second time folded with said margins,—the unoccupied portions of said margins being secured to the folded portions of said corners whereby to effect multiple thickness of material over the corners and on opposite sides of said box.
6. In a folding box, including in combination with a blank for forming a unit of said box, predetermined folding lines on said blank,—the corners of the blank being slotted and portions thereof folded inwardly, opposite outwardly extended portions of said blank folded inwardly and secured to adjacent margins thereof, and a second time folded with said margins,—the unoccupied portions of said margins being secured to the folded portions of said corners whereby

to effect multiple thickness of material over the corners and opposite sides of said box.

7. In a folding box, including in combination with a blank for forming a unit of said box, the corners of the blank being folded inwardly, opposite outwardly extended portions of said blank folded inwardly substantially on a line with main edges of the blank and secured to adjacent margins thereof, a portion of each of said margins, matching the folded portion of the adjacent corner, remaining exposed, said margins being folded on lines substantially parallel with said edge lines and having said exposed portions secured to said corners.

8. In a folding box, including in combination with a blank for forming a unit of said box, the corners of the blank being folded inwardly, opposite outwardly extended portions of said blank folded inwardly substantially on a line with main edges of the blank and secured adhesively to adjacent margins thereof, a portion of each margin matching the folded portion of a corner remaining exposed, said margins being folded on lines substantially parallel to said edge lines and having said exposed portions secured adhesively to said corners.

9. In a folding box, including in combination with a blank for forming a unit of said box, the corners of the blank being slotted diagonally and portions thereof turned inwardly, margins of the blank turned inwardly and secured adhesively to the inturned portions of said corners with their corresponding diagonal edges matching the folding line and their main edges matching the straight edges of the inturned portions of said corners.

10. A blank for forming a unit of a folding box, consisting of an integral rectangular-shaped piece of material having folding lines of the corners thereof predetermined thereon,—said folding lines consisting of lines intersecting at right angles at a point on said material and extending outwardly to adjacent edges thereof, a diagonal line outside said angle extending outwardly from said point of intersection to an edge of the material, and a diagonal slot within said angle extending outwardly from said point of intersection to a corner of the material.

In testimony whereof, I affix my signature.

SAMUEL BERGSTEIN.
